UNITED STATES PATENT OFFICE.

JOSEPH LOREY, OF SAN QUENTIN, CALIFORNIA, ASSIGNOR OF ONE-HALF TO LEONARD MORDAUNT, OF LOS ANGELES, CALIFORNIA.

COMBINATION-PADLOCK.

1,034,263.

Specification of Letters Patent. Patented July 30, 1912.

Application filed June 7, 1910, Serial No. 565,482. Renewed June 4, 1912. Serial No. 701,657.

To all whom it may concern:

Be it known that I, JOSEPH LOREY, a citizen of the United States of America, residing at San Quentin, in the county of Marin 5 and State of California, have invented certain new and useful Improvements in Combination-Padlocks, of which the following is a specification, reference being had thereto in the accompanying drawing.

10 This invention relates to combination padlocks, and the principal object of the same is to provide means which will facilitate the operation of the lock and reduce the wear upon the working parts.

15 In carrying out the objects of the invention generally stated above it will be understood, of course, that the essential features thereof are necessarily susceptible of changes in details and structural arrangements, certain preferred and practical embodiments of which are shown in the accompanying drawings, wherein:—

Figure 1 is a view in vertical section of a padlock constructed in accordance with 25 this invention. Fig. 2 is a top plan view. Fig. 3 is a view partly in side elevation and partly in section of the operating pin and antifriction rollers. Fig. 4 is an end view of the devices shown in Fig. 3. Fig. 5 is a 30 detail perspective view of one of the tumblers of the padlock. Fig. 6 is an enlarged detail sectional view thereof.

Referring to said drawings, it will be seen that the improved padlock comprises a 35 frame the base 1 of which carries the angular end bars 2—3. Said bar 2 has its free end portion provided with a longitudinal recess 4 which is intersected by a transverse opening 5. The other end bar is provided 40 with a pivot ear 6 at its free end to which one end of a shackle 7 is pivotally connected. The other end of said shackle is adapted to be fitted within recess 4 of bar 2 and is provided with a transverse opening 45 8 that aligns with opening 5 of said recess 4. End bar 3 is provided with an intermediate transverse opening 9 that is in alignment with the opening 5 of bar 2 and through which a pin 10 extends that is adapted to 50 pass through opening 5 and enter opening 8 of shackle 7 to lock said shackle to bar 2. Pin 10 is provided with a suitable finger grip 11 and an abutment flange 12 which

limits the movement of said pin in one direction. Said pin is also provided with a 55 longitudinal row of seats 13 for the anti-friction rollers 14.

The pin 10 is retained in a shackle locking or unlocking position by the tumblers 15 which are arranged to form combinations which are necessary to complete before the pin can be moved to engagement with or be disengaged from the shackle 7. Said tumblers are of the same construction and are mounted on pin 10 between the end 60 bars 2 and 3. The tumblers are preferably in the form of disks provided with a central transverse counterbored opening 16 with which a lateral opening 17 communicates. 70

An abutment stop 18 extends through bar 3 and is in the path of movement of the rollers 14 of pin 10 and thereby limits the outward movement of said pin. Said stop is preferably in the form of a removable 75 screw, which may be removed when it is desired to remove the pin 10, such for example to permit the tumblers to be interchanged to permit the combination to be 80 changed.

It will be seen from the foregoing that to release pin 10 from shackles 7, the openings 17 of the tumblers must be in alignment to permit the rollers 14 of said pin to be moved therethrough. It will also be 85 clear that the use of rollers facilitates the operation of the lock and prevents wear on the parts thereof.

What I claim as my invention is:—

1. A combination padlock comprising a 90 frame, a shackle therefor, a pin movable in said frame and controlling the locking of said shackle to said frame, rollers carried by said pin, and means supported by said pin adapted to engage said rollers to normally prevent said pin being moved to a shackle-releasing position. 95

2. A combination padlock comprising a base, a shackle therefor, a pin slidable in said base and controlling said shackle, anti-friction rollers carried by said pin, and combination tumblers carried by said pin and adapted to engage said rollers to prevent the said pin being operated. 100

3. A combination padlock comprising a 105 frame, a shackle therefor provided with a

recess in its free end, a pin slidable in said base and adapted to engage the said recess to lock the shackle to said frame, anti-friction rollers carried by said pin, and 5 combination tumblers carried by said pin and adapted to engage said rollers to prevent the said pin being operated.

In testimony whereof I hereunto affix my signature in presence of two witnesses.

JOSEPH LOREY.
